Primary Examiner — Patricia A Palasik(74) *Attorney, Agent, or Firm* — Oblon, McClelland, Maier & Neustadt, L.L.P.(57) **CLAIM**

The ornamental design for an industrial robot, as shown and described.

DESCRIPTION

FIG. 1 is a front view of an industrial robot of the present invention.

FIG. 2 is a rear view thereof.

FIG. 3 is a top plan view thereof.

FIG. 4 is a bottom view thereof.

FIG. 5 is a right side view thereof.

FIG. 6 is a left side view thereof.

FIG. 7 is a front perspective view thereof; and,

FIG. 8 is a rear perspective view thereof.

Broken lines showing portions of the industrial robot form no part of the claimed design.

1 Claim, 8 Drawing Sheets(56)
